REGULATOR VALVE FOR FLUIDS

Irving Terry, Los Angeles, Calif., assignor to
Arthur H. Kaplan, Los Angeles, Calif.

Application March 21, 1955, Serial No. 35,143

Term of patent 14 years

(Cl. D78—1)

Figure 1 is a perspective view of a regulator valve for fluids embodying my new design;

Figure 2 is a reduced side elevational view of said regulator valve;

Figure 3 is a top plan view of said regulator valve; and

Figure 4 is a bottom view thereof.

I claim:

The ornamental design for a regulator valve for fluids, substantially as shown.
